UNITED STATES PATENT OFFICE

ELWOOD DYMENT, OF CLEVELAND, OHIO, ASSIGNOR TO DYMENT COMPANY, OF CLEVELAND, OHIO, A CORPORATION

RECEPTACLE

Application filed November 19, 1930. Serial No. 496,802.

The present invention relates to receptacles, and more particularly to a receptacle, such as a waste basket, for instance, which is collapsible, and it has for its principal object the provision of a receptacle of this character which may be cheaply manufactured from stiff paper or card-board which will be sturdy in construction, easily manufactured and which will be collapsible substantially flatly so as to occupy but little amount of space and which can be readily handled when not in use.

A further object of the invention is to provide an article of this general character wherein the folding or collapsing of the article is accomplished through instrumentalities comprising a bottom member which may be removed but firmly secured in position when the side members of the receptacle are extended, and the invention further contemplates the provision of novel securing means for this bottom member when the receptacle is positioned for use and the sides thereof extended.

Devices in accordance with this invention can be made in any desired configuration, can be made with any desired ornamental designs, and readily adapt in general to forms and figures of pleasing appearance; and since it is preferred to make these articles out of light materials such as card-board, they are cheap to manufacture and readily adapt themselves to many uses while both utility and pleasing appearance can be combined.

The devices of this invention are characterized, notwithstanding the lightness of the material from which they are constructed, by high degree of strength and rigidity which is imparted through the provision of the bottom member and locking instrumentalities which are provided for securing this bottom member in position when the article is extended; while it is preferred to form the articles of this invention from cheap materials such as card-board, it is obvious any desirable material may be substituted therefor without altering any of the adhered features of novelty.

The embodiment illustrated in the accompanying drawing shows a receptacle of the

nature of waste basket formed in the octagonal configuration and provided with ornamentalations in the nature of cusps or hearts, although it will be apparent that such details do not effect the inventive features; and it will be apparent that the sides of the receptacle may be decorated if desired in any pleasing manner.

In the drawing Fig. 1 illustrates a side elevation of a receptacle of this character illustrated in the form of waste paper basket.

Figure 2 is a sectional view along the line of 2—2 of Fig. 1.

Fig. 3 is a fragmentary sectional view taken along the section line 3—3 of Fig. 2 and showing in dotted lines the direction movement of the bottom member.

Fig. 4 is a side elevation of the receptacle Fig. 1 but showing the receptacle as being collapsed, the position of the bottom member being indicated in dotted lines.

Fig. 5 is a top view of the collapsed receptacle of Fig. 4.

Referring more particularly to the drawing, it will be seen that the receptacle is formed of a plurality of side walls 10 giving any desired configuration to the receptacle, the illustrated form being that of an octagon. Walls 10 are hinged together so as to collapse substantially flatly and may be provided with ornamental designs 11 and 12 if desired.

As will be seen especially from Figs. 2 and 4 a bottom member is provided for the receptacle, this member being indicated by 13; and as illustrated the bottom 13 is secured as shown at 14 to one of the side members, and is conveniently hinged as indicated at 15 so that it will be movable in a vertical plane as indicated by the arrows at Fig. 2; by this means the bottom member 13 is enabled to fold upwardly so that it will fit between the side members when the receptacle is collapsed. This described and illustrated arrangement is a convenient one, although it will be understood that modifications thereof will be readily suggested to one skilled in the art to which this relates.

One of the principal features of the invention is the provision of slits 16 adjacent

the bottom end of the side members 10, or formed elsewhere therein there being thus cut out a plurality of tongues 17, which are resilient and which maintain substantially continuous the surface of each side member. It will be seen that each side 10 can be prepared in this manner so as to have one of these tongues 17, although it is not necessary, as is obvious, to so provide the side to which the bottom 13 is secured; it is also obvious that each of these cut out portions or tongues 17 will provide a shoulder defined by the thickness of the material from which the receptacle is constructed. The bottom member 13 is illustrated as being provided with lugs 18 which will fit into the cut out spaces behind the tongues 17 and will rest upon the aforesaid shoulders, engaging the tongues 17 to force them outwardly so that the pressure exerted by these tongues against the lugs 18 as they rest upon the aforesaid shoulders will firmly retain the bottom member 13 in position when the side members 10 are extended; but the construction is such that the bottom 13 can be readily pushed out of position and folded against the sides of the receptacle so that the walls are then free to be collapsed substantially flatly as illustrated in Figures 4 and 5. The shoulders referred to above are indicated in Figure 2 by numeral 19. It will be seen that when the side members 10 are extended and the bottom member 13 is in position as indicated in the full lines as shown in Figure 3, the bottom 13 will very substantially re-enforce the receptacle and the resilient tongue 17 maintaining substantially continuous, as they do the surface of each side member assures the receptacle being substantially tight so as to prevent even small articles deposited therein falling out.

If desired the bottom ends of the side members 10 can be cut in ornamental fashion as indicated at 20 to increase its pleasing appearance without detracting from the stability of the receptacle.

It will be understood, as above pointed out, and it will be obvious, that many changes in the specific details of the form of device herein described in detail and illustrated in the drawing may be made without departing from the underlying inventive concept; and it will also be obvious that many of such changes in details will become at once apparent to anyone skilled in the art to which this invention relates; and it will be understood accordingly, that it is intended and desired to embrace within the scope of this invention such modifications and changes as may be necessary to adapt it to varying conditions and uses.

What is claimed is:

A receptacle comprising, in combination, collapsible side members, the extremities of which are adapted to form top and bottom

portions respectively, the side members flatly folding together when collapsed, and when expanded forming a receptacle of polygonal configuration, and a member hinged to one of the side members and adapted to extend transversely of the receptacle to form a bottom therefor, the side members being provided, adjacent the bottom ends thereof, with slits to form yieldable tongues between the slits, the bottom member being provided with tabs adapted to engage the said tongues upon expansion of the receptacle and to force the said tongues outwardly from the plane of the sides of the receptacle, the said tongues having their free ends overlying the bottom tabs and exerting force against the ends of the tabs to firmly retain the bottom against accidental displacement while the receptacle is expanded.

In testimony whereof I affix my signature.

ELWOOD DYMENT.
